CLAIM

We claim the ornamental design for counter top table, as shown and described.

DESCRIPTION

FIG. 1 is a front corner perspective view of a counter top table according to an embodiment of the invention. The view from the adjacent front corner being a mirror image thereof.

FIG. 2 is a front elevational view of a counter top table according to an embodiment of the invention. The view from the other three sides being identical thereto; and,

FIG. 3 is a top plan view of a counter top table according to an embodiment of the invention.
